UNITED STATES PATENT OFFICE

ELWOOD C. PHILLIPS, OF EVANSTON, ILLINOIS

TABLE

Application filed August 31, 1927. Serial No. 216,524.

My invention relates in general to furniture and has particular reference to improvements in tables, especially so-called kitchen tables which are used for domestic purposes.

5 The primary object of my invention is to provide a table which may be manufactured cheaply, which may be shipped or stored in knocked-down condition and easily assembled without exercising any undue skill.

10 A further object of my invention is to provide a novel drawer arrangement for tables, particularly a combined drawer guide and reinforcement for the table.

15 A further object of my invention is to provide an ironing board attachment for tables which will enable an ironing board to be combined therewith in such a way that it may be swung into an inactive position out of the way and conveniently manipulated to assume 20 an active position on the table top.

With these and other objects in view the invention will be further described with reference to the accompanying drawing in which

25 Fig. 1 is a top plan view of the table with a portion broken away to show how the legs are joined.

Fig. 2 is a view in elevation from the back of the table showing the position of the ironing board when at rest;

30 Fig. 3 is a top plan view of the table showing the active position of the ironing board;

Fig. 4 is a sectional view on the line 4—4 Fig. 1;

35 Fig. 5 is a bottom view of the ironing board showing the preferred means for securing the same to the cross bar of a manipulating bail;

Fig. 6 is a detail view in side elevation of a part of the table with the ironing board in active position;

40 Fig. 7 is a detail perspective view of the manipulating bail for the ironing board;

Fig. 8 is a detail view of one of the angle iron legs and

45 Fig. 9 is a detail perspective view of one of the leg bolts.

Referring now to the drawing in detail, 10 represents the table top, the same having secured thereto the front side and rear panels 11. The panels are inset relatively of the 50 marginal edge of the top, as clearly shown.

The legs 12 of which there are four, comprise angle irons having relative wide upper attaching ends 13 which taper to narrower opposite ends 14. The angular faces of the legs at the attaching ends 13 are formed to 55 correspond with the angle of the corners made at the joining ends of the panels 11 so that the legs may be attached at these corners with the faces of the angle iron laying flush with the faces of adjacent panels. To secure the legs I prefer to use bolts 15 having angular heads 6 which correspond to the angle of the legs. The legs will be made with holes 17 or other suitable openings for the reception of a bolt and with the angular 60 head 16 embracing the leg on the outside thereof. The bolts will also pass through the corners of the panel assembly and through angle blocks 18, so that nuts 19 may be threaded on the threaded ends 20 of the 65 bolts for drawing the legs in place. The same leg attaching assembly is arranged for at all four corners of the table.

The upper ends of the legs should abut against the underside of the table top as 70 shown at 21 in Fig. 2.

With this manner of securing the legs I can accomplish many desirable results. First of all it will enable the tables to be shipped or stored knocked down. The top and panels 75 all in one piece and the legs disconnected and nested together. By this means I can place as many as six or more tables in a tier occupying the same space that only accommodated three with the legs on. Then again the saving in making my table will be an added advantage.

Durability and rigidity is still another feature of my improvements.

In the front panel of the table is an opening in which a drawer 22 is slidably mounted. The drawer has a block 23 or the like secured to the underside of the back end with a slot therein for the reception of a guide rod 24 which is secured to the front and back 85 panels. This rod serves as a guide for the drawer and also as a brace for the panels of the table. The block 23 serves furthermore as a stop for preventing the complete withdrawal of the drawers. The block in this 90 95 100

capacity will abut against the inside of the front panel at the limit of the withdrawal of the drawer.

Referring now to the ironing board attachment I prefer to employ a bail 25 for pivotally connecting the board to the table. This bail will usually be made from a single length of iron rod, of a gauge suitable for the purpose and bent as shown to provide for a cross-bar 26 and two arms 27.

The bail will thus be arranged to straddle the table with the arms 27 pivotally connected to the side panels. For this connection I can turn the extremities of the arms into eyes 28 and use bolts, pins, screws or the like for the pivots.

The board 29 will be cut out on its underside to leave a longitudinal groove 30. This groove preferably terminates short of the blunt nose 31 of the board but is open at the opposite end 32 of the board. The cross bar 26 of the bail 25 is hingedly connected in this groove by the clips 33. The clips are made with sleeves 34 in which the cross bar is loosely confined so that the board is not only pivoted to the cross bar but also free to slide thereon. The attaching bases of the clips are flat so that they will lay flush in the groove and with screws 35 anchoring the same in properly spaced relation.

With this bail the board is mounted to swing from a position at rest in back of the table substantially parallel with the legs 12 and below the top 10 to an active position upon the table top. The slideable mounting of the board on the cross bar 26 will also permit the table to be moved to a limited extent across the table longitudinally of the cross bar so as to project the end thereof in advance of the table as shown in Fig. 3. This extended position of the board is useful in ironing skirts or other pieces that must be inserted over the end of the board.

The bends 37 between the cross bar 26 and the arms 27 is such as to leave the cross bar offset with respect to the arms. The reason for this is to enable the arms to clear the edge of the table top and also permit the cross bar to work in the clips in a manner to enable the board to swing from a horizontal position into a perpendicular position when moving from the table top to a position behind the table. The groove 30 is cut as best shown in Figs. 4 and 6, to accommodate the offset bend 35 when the board is in a position as shown in Fig. 4.

Obviously those skilled in the art may make various changes in the construction of the table and ironing board attachment without departing from the spirit of the invention as defined by the subjoined claims and I therefore do not care to be limited to the precise construction shown and described.

I claim:

1. An ironing board attachment for a ta-

ble comprising a bail for pivotal connection with opposite sides of the table and shaped to straddle the table with freedom of swinging movement, means for securing the ironing board to the bail comprising a longitudinal groove in the bottom of the ironing board for the reception of the bail, and clips in said groove for securing the bail therein with freedom of rotation.

2. An ironing board attachment for a table comprising a bail for pivotal connection with opposite sides of the table and shaped to straddle the table with freedom of swinging movement, means for securing the ironing board to the bail comprising a longitudinal groove in the bottom of the ironing board for the reception of said bail, and means for securing the bail in said groove with the ironing board free to slide longitudinally thereon.

3. An ironing board attachment for a table comprising a substantially U-shaped bail, said bail comprising a cross bar to which the ironing board is pivotally attached and arms for pivotally mounting the bail to the side of the table with freedom of swinging movement, said cross bar being offset with respect to the plane of said arms and the arms being disposed at right angles to the projection of said cross bar on said plane.

4. An ironing board attachment for a table comprising a substantially U-shaped bail, said bail comprising a cross bar to which the ironing board is pivotally and slidably attached and arms on the bail for pivotally mounting the bail to the sides of the table with freedom of swinging movement, said cross bar being offset with respect to the plane of said arms, and the arms being disposed at right angles to the projection of said cross bar on said plane.

5. An ironing board attachment for a table comprising a substantially U-shaped bail having a cross bar pivotally and slidably mounted in the longitudinal groove on the under side of the ironing board, attaching arms for said bail bent at right angles to said cross bar and pivotally attached to the side of the table, said cross bar being offset with respect to said arms and lying in said groove along a substantially perpendicular wall thereof, the opposite wall of said groove being dished out to accommodate the curves in the arms of the cross bar when the ironing board swings about its pivotal connection with the cross bar.

In witness that I claim the foregoing as my invention, I affix my signature this 29th day of August, A. D. 1927.

ELWOOD C. PHILLIPS.
